DESIGN FOR AN ELECTRICAL CONNECTER

Lurelle Guild, Darien, Conn., assignor, by mesne assignments, to Electrolux Corporation, Dover, Del., a corporation of Delaware

Application November 16, 1937, Serial No. 72,927

Term of patent 14 years

To all whom it may concern:

Be it known that I, Lurelle Guild, a citizen of the United States of America, residing in Darien, Connecticut, have invented a new, original, and ornamental Design for an Electrical Connecter, of which the following is a specification, reference being had to the accompanying drawing, forming a part thereof.

Fig. 1 is a plan view of the electrical connecter, showing my new design.

Fig. 2 is an end view of the electrical connecter, and

Fig. 3 is a perspective view of the electrical connecter.

I claim:

The ornamental design for an electrical connecter, as shown.

LURELLE GUILD.
